UNITED STATES PATENT OFFICE.

DONALD G. LITTLE, OF WILKINSBURG, PENNSYLVANIA, ASSIGNOR TO WESTINGHOUSE ELECTRIC & MANUFACTURING COMPANY, A CORPORATION OF PENNSYLVANIA.

TUBE SUPPORT.

Application filed June 27, 1925. Serial No. 39,920.

- This invention relates to vacuum-tube devices of the type used in oscillation generators and particularly to means for supporting the tubes and securing them in place.
- It is an object of this invention to provide a supporting device by means of which the tubes may be handled and mounted more safely and expeditiously.
- 10 It is a further object of this invention to provide a guiding means which will enable the tube, and the plate to which it is secured, to be inserted in the apparatus without danger of accident to the tube.
- 15 It is a further object of this invention to provide a vacuum-tube plate with securing and supporting devices, which shall be simple, inexpensive to manufacture, will not easily get out of order, and shall prevent all 20 tendency of the tube to rock upon its support.
- Other objects of the invention and details of the construction will be evident from the following description and the accompanying drawing, in which:
- Figure 1 is a side elevation of a preferred form of my tube and its support;
- Fig. 2 is a top plan view, and
- Fig. 3 is a similar view of a modification.
- 30 The apparatus in which oscillations are developed for high-power radio-sending stations includes a frame upon which the several parts are mounted. Among said parts are a number of vacuum tubes. In 35 Fig. 1, the frame is indicated by two members 1 shown in section. These members carry insulators 2, upon the upper ends of which screw-threaded engaging members 3 are provided.
- 40 The plate 4 is preferably of sheet metal, heavy enough to have the necessary rigidity. Preferably, it is of cast aluminum, but plates of heavy sheet brass have been used with satisfactory results. The plate is of 45 such shape that a central portion is large enough to accommodate one or several tubes. Its end portions project far enough beyond the tubes to position them at a distance from the insulators 2 and from the members 50 of the frame.
- At one end, the plate is provided with a longitudinally-extending notch or recess 5 having its mouth at the end of the plate. The inner end of this recess fits the engaging member 3. The mouth of the recess is flared in order that the plate may be readily positioned with the notch embracing the engaging member.
- At the opposite end of the plate, a recess or notch 6 extends at right angles thereto. 60 The mouth of the notch 6 is in one side of the plate near the end. The engaging members 3 are provided with wing nuts 7 or other clamping means. If desired, these nuts may serve as binding posts to attach 65 conductors such as 8.
- The center of the plate is provided with one or more circular openings 11, one for 70 each tube that the plate is intended to support. Each of the openings is larger than the glass cylindrical part 12 of its tube, but not enough larger to permit the seal 13 to pass. This seal contains the conductor which extends to the grid of the tube. It is preferable that it be on the side of the 75 tube and not at the end where the other conductors 14 emerge. In order to permit the tube to be inserted in the plate without danger of striking the seal 13 against the plate, recess 15 is provided.
- In the case of very large tubes, the seal 80 13 may extend so far that, in order to leave ample room for manipulating the tube, the recess 15 is prolonged into a passage 16 shown in Fig. 3 which extends completely 85 to the outer edge of the plate. When this is the case, the plate 4 must be made heavy enough to afford ample support for the tubes even though the continuity of one or more 90 edges of the plate is broken.
- The tubes used in connection with high-power oscillators are provided with a water jacket 18 having an inlet 19 and an outlet 20. At the lower end, the water jacket is provided with a flange 22 which contacts 95 with a metal member 23. The member 23 is electrically a part of the plate or anode of the tube. A number of bolts 24 extend through the flange 22 and the metal member 23, clamping them together to make a water-tight joint. Preferably, the joint is supplied with a gasket of rubber or other suitable packing material to prevent leakage.
- The bolts 24 extend below the member 23 100 distances, which, because of irregularities of manufacture, will not be equal. In order to avoid the unsatisfactory seating, of the tube which would ensue from this inequality, opening 11 is large enough to permit the ends of the bolts to pass below the upper 110

surface of the plate 4. Inwardly projecting lugs 25 provide ample bearing surface for the member 23.

Two or more threaded studs 26 are provided for each tube, by means of which the tubes may be clamped to the plate 4 and good electrical connection thus provided between the member 23 and the lugs 25. Members 27 transmit to the flange 22 the pressure necessary to ensure firm clamping and good electrical contact. The members 27 are long enough to extend from the studs 26 nearly to the inner edge of the flange 22. Ample bearing surface between the members 27 and the flange is thus provided.

In order that the pressure of the clamping member 27 may be delivered directly and not obliquely to the flange, the outer end of the member is provided with a lip 28 which is at an angle to the length of the member 27 and of sufficient width to position the outer end of the member 27 at the same height above the plate 4 as the upper surface of the flange 22. Nuts 29 on the threaded studs 26 to engage the members 27 and, through them, exert, when tightened the necessary pressure on the flange 22.

When the operator has occasion to place a tube in the machine, he first places the plate 4 over the glass end of the tube, the opening 11 surrounding the tube, and the water jacket resting upon the lugs 25, with the heads of the bolts 24 projecting into the holes 11. He then places the clamping members 27 upon the studs 26 and fastens them in place by the wing-nuts 29. Tightening these wing-nuts makes a firm connection between the tube and the plate. If several tubes are associated with one plate 40 each is placed in position in the manner just described.

The tubes and plate are then lifted as a unit. The large area of the plate relative to the tubes serves as a guard, making it unlikely that the operator will strike the glass of the tube against any part of the apparatus.

When inserting the tubes in place, the operator places the notch 5 astride of the one of the engaging members 3. The plate with its tubes is fairly heavy and the operation of getting it into place without a guide is difficult. For this reason, the flared mouth of the notch 5 is of great assistance. While the one end of the plate, with its tubes, is held in position by the engagement between the notch 5 and the engaging member 3, the plate is swung about the engaging member 3 as a pivot, and the notch 6 receives the other engaging member 3.

The positioning of the plate is thus easily and quickly accomplished and, during such positioning, the motion of the plate is guided, whereby the danger of the tubes

striking against some part of the machine is minimized.

The conductor 8 is then placed about the engaging member 3 and fastened thereto by the wing nut 7. It is not necessary that each of the engaging members 3 fasten a conductor in place, but if two different conductors are to be connected to the anodes of one set of tubes, the second engaging member 3 is available for a second conductor. When the nuts 7 have been tightened, the tubes are secured in place in the machine.

It will therefore be apparent that my invention provides means by which tubes may be quickly inserted in the apparatus without risk of damage to the tubes. Changes are frequently made hurriedly, because it is desired to minimize any interruption to the service rendered by the machine, this is of importance.

It will be evident to those skilled in the art that many modifications of this invention are possible without departing from the spirit thereof. I, therefore, do not intend the specific illustration and description given herein to be construed as a limitation.

I claim as my invention:

1. In combination, a water-jacketed tube, having a flange between its ends and at one end of the water jacket, fastening means extending through and projecting from said flange, a supporting plate having an opening to receive the unjacketed part of said tube, and lugs on said plate extending into said opening to support said tube by engagement with said flange, said lugs being of such width as to be received between the projecting portions of said fastening means.

2. In combination, a tube having a laterally-extending seal and a water jacket, a flange at one end of said water jacket and between the ends of said tube, a supporting plate having an opening therein of approximately the size of said flange, to receive the unjacketed end of said tube, said plate also having a recess extending from said opening such distance as to permit passage of said seal.

3. In combination, a tube having a water-jacket extending over a portion only of its length, a flange at one end of the water-jacket, a plate for supporting said tube, and means for clamping said flange to said plate, said clamping means comprising a member having a laterally-extending lip for engaging said plate, a threaded member secured to said plate and extending through said member and a co-operating threaded fastener for engaging said member.

In testimony whereof, I have hereunto subscribed my name this 24th day of June, 1925.

DONALD G. LITTLE
